Grand Rapids, Mich.

Filed May 22, 1973, Ser. No. 362,852

Term of patent 14 years

Int. Cl. D6—04

U.S. Cl. D6—161

FIG.1

FIG.2

FIG.3

FIG.7

FIG.4

FIG.5

FIG.6

FIG. 8

FIG. 9

FIG. 1 is a perspective view of a desk embodying the design of our invention;

FIG. 2 is a front elevational view of the desk;

FIG. 3 is an end elevational view of the desk;

FIG. 4 is a rear elevational view of the desk;

FIG. 5 is a generally rear perspective view of the desk;

FIG. 6 is a top plan view of the desk;

FIG. 7 is a cross-sectional view taken along plane VII—VII of FIG. 2;

FIG. 8 is a perspective view of an alternative embodiment desk embodying the design of the invention; and

FIG. 9 is a perspective view of yet another alternative embodiment desk embodying the design of the invention.

We claim:

The ornamental design for a desk, substantially as shown.
